UNITED STATES PATENT OFFICE

107,015

DESIGN FOR AN ARTIFICIAL BOUTONNIERE

Harry Haimes, New York, N. Y.

Application October 6, 1937, Serial No. 71,988

Term of patent 3½ years

To all whom it may concern:

Be it known that I, Harry Haimes, a citizen of the United States of America, residing in New York city, in the Borough of Manhattan, county and State of New York, have invented a new, original, and ornamental Design for an Artificial Boutonniere, of which the following is a specification, reference being had to the accompanying drawing, forming part thereof, wherein,

Figure 1 is a plan view of an artificial boutonniere showing my new design.

Figure 2 is a side elevational view of the boutonniere shown in Figure 1.

The characteristic feature of my design resides in the illustrated buttons in combination with the boutonniere as shown.

I claim:

The ornamental design for an artificial boutonniere, substantially as shown, and described.

HARRY HAIMES.
